(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The present application is filed concurrently with and incorporates by reference U.S. patent application Ser. No. 17/839, 157, entitled "System with Servers and Management Logic for Improved Communication Handling Via Receptionist-Center User Interface".

The FIGURE is a front view of a display screen or portion thereof with graphical user interface showing the present design.

The outermost broken lines in the FIGURE show a display screen or portion thereof. The remaining broken lines show portions of the graphical user interface. All broken lines form no part of the claimed design.
